UNITED STATES PATENT OFFICE

EDGAR M. CLARK, OF NEW YORK, N. Y., ASSIGNOR TO STANDARD I. G. COMPANY

METHOD AND APPARATUS FOR HYDROGENATION AND DISTILLATION OF LOW-SULFUR PETROLEUM OILS

Application filed January 26, 1928. Serial No. 249,585.

This invention relates to the art of hydrogenating hydrocarbon oils. More particularly, it comprises the combination of a battery of stills with hydrogenating equipment, the hydrogenated product being distilled in the battery. In my application, Serial No. 249,584, filed of even date herewith, this general combination is broadly claimed and is exemplified by equipment specifically different from that described and claimed herein.

The present invention will be fully understood from the following description, read in connection with the accompanying drawing, in which the figure is a diagrammatic vertical section of equipment suitable for practicing the improved method.

Referring to the drawing, 1, 2, 3, 4, and 5 denote a battery of series-connected stills. These may be of the usual shell type having bell-cap plate towers 6, 7, 8, 9, and 10. It will be understood that the number of stills may be varied. A refluxing coil 11 is installed in the upper part of each tower and receives a suitable cooling medium, preferably the oil to be treated, through pipe 12 and branch pipes 13. The coils 11 discharge through lines 14 into the hot oil line 15. The inlets and outlets to the coils 11 are valve controlled so that the amount of oil passing through the coils may be regulated to secure the desired cooling effect.

Vapors are taken off from each still through lines 16, the stills being maintained at progressively higher temperatures in the usual manner. Steam may be injected into the bottom of each still through a spray pipe 17. Liquid oil is transferred from one still to the next in series through lines 18, 19, 20 and 21. Pumps may be provided in these lines but it is preferred to utilize a steam lift effect as by injecting steam through a pipe 22.

Branch lines 23 and 24 lead from lines 18 and 19 and discharge into a header 25, which also receives liquid oil from the last still 5 through a line 26. The hot oil line 15 and the cold feed line 12 are connected by a line 27. This conveys the oil to the tower 6 of still 1.

The hot oil from header 25 flows through pipe 28 into the heat exchanger 29 and thence

by a pipe 30, in which a pump 31 is installed, to a heating coil 32, mounted in a suitable furnace setting 33. The coil discharges through line 34 and branch lines 35 into one or more reaction chambers or reactors 36. These are constructed to withstand the action of hydrogen at very high pressures and temperatures. They are heat insulated and may contain electric heaters or other suitable internal means (not shown). A stirrer 37 may also be installed in each reactor, or the injection of oil and hydrogen may be depended upon for agitation.

Line 38a receives hydrogen from the condensate drum 39 (subsequently described) through line 40. Line 38a conveys the hydrogen to the lower part of a purifying tank 41, into the upper part of which a purifying solution, such as sodium hydroxide or sodium carbonate solution, is introduced through spray head 42. The purifying solution is drawn off through line 43 and may be revived for further use. The hydrogen then passes through line 44 into the lower part of a second purifying tank 45, into the upper part of which a solvent for hydrocarbons is sprayed at 46. The solvent is withdrawn through line 47 and the dissolved hydrocarbons are removed by distillation in the well known manner.

The purified hydrogen leaves the tank 45 through line 48 and is forced by pump 49 through lines 48a and 50 into the reactors 36. Additional high pressure hydrogen, or a gas containing hydrogen in effective amounts, is supplied through line 38 to line 48a. The oil lines 35 and the hydrogen lines 50 preferably discharge near each other at the bottom of the reactors. A line 48b conveys hydrogen from line 48a to a mixing device 30a in the oil line 30. The mixing device may be porous or perforated plates, a baffle tower, or other means for bringing liquid and gas into intimate contact.

Lines 51 are provided for withdrawal of material from the lower part of the reactors, and gases and vapors are taken off through lines 52, which discharge into a manifold 53. Preferably lines 51 connect with line 30, so that charge may be continuously circulated.

through the reactors 36 and coil 32. Gases and vapors pass to the heat exchanger 29 and then to the condensing coil 54. This discharges into the drum 39. A pressure control valve 55 is installed between the coil 54 and the drum 39.

Hydrogenated condensate preferably flows from this drum through line 56 to line 56a, branch lines 23a and 24a, and thence into towers 7 and 8 of stills 2 and 3, respectively. Line 56 is also connected with line 27 and through this with tower 6 of still 1. A valve 27a is provided in the connection.

In the operation of the equipment shown, 15 a suitable oil, advantageously crude petroleum, having a relatively low sulfur content, is supplied through line 12 and preheated in coils 11. The oil may be a pipe line crude from Oklahoma containing sulfur 20 within the approximate limits of about 0.1 to 0.3%. Other oils are of course suitable, provided they do not contain sufficient sulfur in the low-boiling fractions to render them commercially undesirable. The flow of hydrogen is indicated by feathered arrows and the flow of other fluids by plain arrows. The preheated oil is forwarded through line 27 to tower 6 of still 1. The topped crude and other residual oils are taken off, for example, from 25 stills 2 and 5, and flowed through header 25 to heat exchanger 29. The oil flows from this heat exchanger through line 30 to the coil 32, in which it is heated to a temperature of about 750-950° F., and passes at this temperature 30 to the reactors 36. The pressure in the battery of stills is preferably substantially atmospheric and the pump 31 raises the oil to the required pressure.

The hydrogen or hydrogen-containing gas 40 is raised to the proper pressure by pump 49 and is injected through lines 50 into the reactors, wherein it is intimately mixed with the oil. The hydrogen in lines 50 may be passed in heat exchange relationship to the 45 products from the reactors in lines 52. The temperature in the reactors is maintained at about 750 to 950° F. and at a pressure of 50 to 200 atmospheres or more, preferably about 200 atmospheres. Gases and vapors from the 50 reactors are cooled by heat exchange with the oil passing through heat exchanger 29 and the normally liquid products are condensed in cooler 54. These products are preferably forwarded through lines 56, 56a, 23a and/or 24a to the stills 2 and/or 3. If desired, some or all of the hydrogenated product may be forwarded through line 27 to tower 6. The stills are usually held at temperatures progressively increasing from about 350° F. to 60 700° F., taking off successively light naphtha, heavy naphtha, kerosene, gas oil, and lubricating oils. Superatmospheric pressure or subatmospheric pressure may be maintained on one or more of the stills, in accordance 65 with well-known practice.

Instead of simple condensation and gas release as described, it will be understood that any desired degree of rectification may be substituted. When rectification is used, lighter products may be taken off and only 70 the heavier residue forwarded to the stills.

The unvaporized oils from stills 1, 2 and 5, or such other residual oils as are passed to the hydrogenating step, are largely freed from sulfur, if present, by the action of 75 hydrogen in reactors 36. The sulfur is mostly converted into hydrogen sulfid and is removed by washing with alkali solution in tank 41. Methane and other light hydrocarbons carried along with the hydrogen are 80 absorbed by the oil in tank 45.

It will be noted that the entire feed oil does not pass through the hydrogenation equipment. Lighter fractions are distilled off in 85 stills 1 and 2, only unvaporized oil from one or both these stills passing to line 25. This method of operation is especially advantageous for those oils the low-boiling fractions of which contain only small amounts of sulfur. High-sulfur naphthas and the like should be passed through the hydrogenation equipment for the reduction of the sulfur content, as described in the copending application above mentioned.

Catalysts are ordinarily provided in the 90 reactors for promoting the reaction between the oil and hydrogen. When charge is recirculated through lines 51 and 30, the catalyst accompanies the oil through coil 32. Hydrogen may also be passed through line 48b for admixture with the oil passing through the coil. Finely pulverized metal oxids, especially a mixture of 90% chromium and 10% molybdenum oxide are recommended. Such catalysts are maintained in suspension by the 95 agitation provided in the reactors. The amount of catalyst may be varied greatly. When using the mixed oxid catalyst described, about one-third by volume of the oil 100 in the reactors at any one time, is generally satisfactory. The amount of hydrogen supplied may also be widely varied. By way of example, it may be said that about 10,000 to 15,000 cubic feet of hydrogen is required 105 for the satisfactory treatment of each 50 gallon barrel of oil passing to the reactors.

One or more secondary reactors containing catalytic bodies may be provided to receive the gases and vapors from reactors 36. The secondary reactors are supplied with an additional quantity of high temperature hydrogen, in the manner described in the copending application referred to above. A pressure control valve may be provided in the line 110 between the primary and secondary reactors and the latter may be run at the same pressure, or at a higher or lower pressure. Electric heaters or the like may be installed in the secondary reactors.

It will be understood that the foregoing 115

description is merely illustrative of preferred forms of the invention and that various changes and alternative arrangements and procedures may be adopted within the scope of the appended claims in which it is my intention to claim all novelty inherent in the invention as broadly as the prior art permits.

I claim:

- 10 1. Process for obtaining valuable products from hydrocarbon oil which comprises distilling from the oil the lowest boiling fraction, subjecting the residual oil to the action of hydrogen under a pressure in excess of 50 atmospheres and at temperature above 750° F. but below 950° F., removing vapors evolved in the hydrogenation, cooling the same, passing the hydrogenated condensate to the distilling operation and distilling same with fresh unhydrogenated oil.
- 15 2. Process for obtaining a plurality of valuable fractions from a crude petroleum oil having a low sulfur content, which comprises distilling off the lowest boiling fraction of the oil in the first of a series of distillation zones, continuously passing a portion of the undistilled residue successively through the other distillation zones of the series, continuously subjecting another portion of the undistilled residue from the first distillation zone to the action of hydrogen under pressure in excess of 50 atmospheres and at temperature above 750° F. but below 950° F., removing vapors evolved in the hydrogenation, cooling the same, passing the hydrogenated condensate to the first of the series of distillation zones, and continuously removing from each of the zones a vapor comprising a mixture of hydrogenated and unhydrogenated oil.
- 20 3. Process according to claim 2 in which the undistilled residue from the last of the series of distillation zones is subjected to the hydrogenation.
- 25 4. Process for obtaining a plurality of valuable products from a crude petroleum oil having a low sulfur content, which comprises continuously passing the oil through a series of stills, continuously withdrawing a portion of the undistilled residue from one or more of the stills, subjecting the withdrawn oil to the action of hydrogen under pressure in excess of 50 atmospheres and at temperature above 750° F. but below 950° F., condensing vapors evolved in the hydrogenation, passing hydrogenated condensate to one or more stills of the series, and continuously removing from each still a vapor comprising a mixture of hydrogenated and unhydrogenated products.
- 30 5. Continuous hydrogenation equipment, comprising a series of stills, means for passing preheated oil into a preliminary still of said series, means for passing a portion of the residual oil through the remaining stills

of the series, separate means for taking off another portion of the residual oil from said still, a heater, means for passing said residual oil through said heater, a reactor, means for supplying hydrogen at high pressure thereto, means for passing the oil from said heater to said reactor for intimate commingling with the hydrogen therein, means for separating normally liquid products from the gases and vapors from said reactor, and means for returning said normally liquid products to the series of stills.

6. Apparatus according to claim 5, in which means are provided for taking off residual oil from a still other than the first in series, and for passing residual oil from such other still to the reactor.

7. Continuous hydrogenation equipment, comprising a series of stills, means for passing a portion of the residual oil from the first still successively through the other stills of the series, separate means for removing residual oil from the first and last stills of said series, a heater, means for passing the residual oil through said heater, a series of reactors, means for passing oil from said heater to said series of reactors, means for supplying a gas rich in free hydrogen and at high pressure thereto, means for separating normally liquid products from the vapors from said reactors, and means for returning said normally liquid products to an intermediate still of the said series of stills.
